(57) CLAIM

The ornamental design for a battery case, as shown and described.

DESCRIPTION

FIG. 1 is a Front elevational view of a battery case showing my new design;

FIG. 2 is a Rear elevational view thereof;

FIG. 3 is a Left side view thereof;

FIG. 4 is a Right side view thereof;

FIG. 5 is a Top plan view thereof; and,

FIG. 6 is a Bottom plan view thereof.

The broken lines in the drawings are for the purpose of illustrating portions of the battery case that form no part of the claimed design.
